UNITED STATES PATENT OFFICE.

JOSEPH KAUFMAN, OF NEW YORK, N. Y., ASSIGNOR TO AMERICAN SAFETY RAZOR CORPORATION, OF NEW YORK, N. Y., A CORPORATION OF VIRGINIA.

CONTAINER.

Application filed October 3, 1924. Serial No. 741,377.

My present invention relates generally to containers and to their association and co-ordinately to such an association of containers as will on the one hand suggest and drive home effectively the advertising and selling features of the article contained in one of them, and as will on the other hand give to the user of the article a physical evidence of the benefits resulting from its use.

As is well known, the development of self-shaving is more or less tied up with the development of what is known as the safety razor, of which there are numerous types on the market.

While the factors of convenience and cleanliness have had a great deal to do with the almost universal practice of men to shave themselves, the greatest factor that has resulted in its universal development, and which factor has become of the greatest importance, is the saving resulting, particularly in view of the fact that the cost of shaving in establishments known as barber shops, has increased with the general rise in the cost of all commodities and of service.

In order to bring home this factor of saving and consequently to increase the use of safety razors and their sale, slogans such as "Shave and save" have been adopted to put in as pithy and as attractive a way, the fact that by shaving oneself with an outfit the initial cost of which is relatively small and the upkeep of which is also correspondingly small, a relatively large saving can be effected.

It is obvious that slogans such as "Shave and save" have been presented to the individual hitherto by advertisements of various characters, which, however, do not generally bring home the effect thereof at the time desired, namely, just at the time when the user is actually shaving.

One of the objects of my invention, is to form a razor case container of such a character that the slogan "Shave and save" or its import, will be forcibly presented to the user of a razor contained in such case every time the individual uses such razor.

The human mind is limited, however, more or less to the specific, and in calculating savings, the average person keeps in mind only the fact that a single shave costs, let us say, twenty cents at a barber shop, and that

a similar operation at home, prorated for a sufficiently long time, taking into consideration the initial cost and the cost of replacement and upkeep, may be, say only two cents, thus giving a saving of eighteen cents. The average individual, however, does not sit down to calculate, and even after he has done so, does not keep in mind that while at each shave he saves eighteen cents, that in the aggregate, for a period of a year, the saving will run over and above \$60 and even where he does realize and keep in mind this aggregate of saving, there is no actual evidence thereof as by a distinct segregated accumulation of such saving over a period of time.

Another important object of my invention is the provision of such a character of case for the safety razor, which will not only at all times remind a man of the fact that he is saving by shaving himself and will suggest to him the fact that he permit the savings to accumulate, but which will give him a physical arrangement whereby accumulations of such savings can be made so that at the end of any stated period, as for instance, at the end of six months or a year, he can not only tell definitely what the total saving has been as against the total cost, but in addition he will have such saving in a segregated fund.

My invention further provides an association with a razor, of a money container, so that when a person opens the shaving container to run over the razor for a shaving operation there will be right at hand not only a reminder of the economy to be effected, but there will also be presented to the user a coin slot leading to a container in which the money so saved at the particular shave can be put away and kept segregated.

Another important object of my invention is the provision of a new, useful, simple, economically constructed and effective container, and more particularly one intended to associate containers having a single aim in view, one of which is to serve as a bank.

For the attainment of these objects and of such other objects as may hereinafter appear or be pointed out, I have illustrated one embodiment of my invention in the drawings wherein:

Fig. 1 is a perspective view of the con-

tainer with one end open, exposing the shaving outfit.

Fig. 2 is a perspective view of the container with the opposite end open.

5 Fig. 3 is a vertical cross-section through the container; and

Fig. 4 is a view similar to Fig. 1 with the contents removed and parts broken away so as to show the detailed construction.

10 Upon comparing Figs. 1 and 2 of the drawing, it will be observed that my container comprises generally the body portion 10 which is open at opposite ends and is divided intermediate such open ends by the 15 partition 11 into upper and lower compartments 12 and 13 for which compartments the members 14 and 15 serve as closures.

The body member 10 is preferably formed of two sections 16 and 17, each of which is 20 preferably made of a metal stamping and which for the purposes of the present disclosure are alike in all respects and the description of one of which will therefore suffice for both. The sections 16 and 17 are preferably stamped so as to provide each with a continuous upstanding wall 18 forming four sides of the section and the bottom 19 which is cut away as shown in the drawings in order to reduce the weight of the section, as 25 well as for other purposes that will appear, thus giving the bottom 19 the formation of a flange continuous with the four sides of the wall 18.

The two sections 16 and 17 are then assembled by causing the bottom flanges of the tube to be brought into contactual association, these bottom flanges then being permanently united in any preferred or desired manner as by the buttons 20.

40 This body portion of the container is then finished exteriorly in any desired or preferred manner as by passing thereabout a covering member 21 which can be made of any readily flexible, yet relatively stiff material, such as cardboard, and the ends of 45 which are joined in an overlapped position as shown at 22 in Fig. 3. The body member is then finally finished off exteriorly by an outermost covering 23 which may be made of a material to imitate leather, which is 50 shown as arranged to be passed over the upper and lower edges of the assembled sections 16 and 17 and the cover member 21.

In the upper compartment 11 is positioned 55 the composite structure comprising the base member 26 and the block 27, shaped as shown in Figs. 1 and 3 of the drawing and arranged so as to form seats and compartments for a razor and a blade receptacle as 60 shown in Fig. 1 of the drawing. The members 26 and 27 are covered preferably as shown in these figures with an attractive plush-like material for purposes of convenience and attractiveness. The base member 65 26 serves, as will be understood, to complete

the bottom closure partly formed by the flange 19 which is cut away as already described.

The block 27 is provided with the slot 30 passing therethrough and in order that the 70 inclusion of this slot may not reduce the available area of the container 25, it is placed relatively close to one wall, preferably to the front wall of the body member 10 and the base member 26 is cut away in registry 75 with the slot and as shown in Fig. 3 of the drawing. The flange is similarly cut away so that on the one hand, the slot does not reduce materially the space of the container 25 and on the other hand, the flange 80 19 which forms substantially the main support for the partition 11 intermediate to the top and bottom of the body member 10 serves its function effectively.

The lower container member 32 is also 85 provided with a base member 33 made of any desired or preferred relatively stiff material such as cardboard, this member 33 being slotted as shown at 34 in registry with the cutout 35 in the flanges 19 and the cutout 90 in the base member 26 and the slot 30. In this manner, I provide a slot 30 of a size to receive coins of various values which slot is open at one end to the upper receptacle 95 and in which, as stated, are to be received the shaving implements that form the partition into the lower compartments 12.

The cover members 14 and 15, the former 100 for the upper compartment 12 and the lower for the lower compartment 13 are of any desired or preferred character, contours, and dimensions and are preferably pivoted to the bottom member 10 as by the hinge members 40 and 41 secured together by 105 pintle 42.

Upon viewing Fig. 4 of the drawing, it will be observed that I use the leaf spring 44 which is of such a character that it maintains the covers in either the closed or open position. The cover members 14 and 15 110 which may preferably be alike in all respects, each comprise the stamping 45 having the continuous side walls as shown and provided with the flange 46 cut away centrally at 47 and also cut away at predetermined points as shown at 48, through which openings 48 are received the prongs 49 cut out from the closure base member 50 and bent around the flange 46.

The side members 45 and the cover base 115 member 50 are finished off exteriorly in any desired or preferred manner as by being covered by a material 51, in imitation of leather.

Attached to the front of the wall 17 of the container 13, is the member 53, (see Figs. 2 and 3) provided with an opening 54 in which is to be received catch 55, movable within the casing 56 and controlled to move to its locked and unlocked position by means 120 125 130

of a conventional type of key. The compartment 12 is as already stated intended to contain a safety razor outfit as shown in Fig. 1 of the drawing, whereas the compartment 13 is intended to serve as a savings bank and for this reason as has already been described, the compartment 13 is arranged to be locked, whereas the compartment 12 is arranged to be opened at will and not locked. 10 It will be understood from the description thus far given, that I have provided a safety razor container, which is so constructed that anyone attempting to use the razor container therein for shaving, will not only necessarily have brought to his attention the fact that there is a saving resulting from shaving himself, but also that such a saving should be deposited in the compartment 12 through the opening 30. In addition to this, the 20 closures for this container are so constructed that while the closure for the razor compartment can be opened and closed conveniently and without difficulty, the closure for the savings bank can be opened only by the operation of a key.

Having now described my invention and illustrated its use, what I claim as new and desire to secure by Letters Patent is:

1. In a device of the character described, 30 a container made up of a plurality of sections, each section being in the form of a metal stamping, having a continuous front, side and rear wall construction and a flange extending inwardly therefrom and continuous with the walls, the sections being assembled with the flanges in contact, whereby the container is formed with its interior divided by the flanges into upper and lower compartments, and means associated with the flanges 35 for complete, dividing partition between the

compartments, a flexible covering passed about the container and a finishing covering passed over the upper and lower edges of the assembled sections.

2. In a device of the character described, 45 a container having compartments upon two opposite faces thereof and made up of a plurality of sections, each section being in the form of a metal stamping, having a continuous front, side and rear wall construction and a flange extending inwardly therefrom and continuous with the walls, the sections being assembled with the flanges in contact, whereby the container is formed with its interior divided by the flanges into upper 50 and lower compartments, and a coin slot opening through the flanges from one compartment to the other, closures pivoted at opposite faces of said container to close the compartments and means associated with each pivot to maintain the closures in either 55 open or closed position.

3. A shaving and saving device of the character described, including a container 60 for a razor and savings made up of a plurality of tray-like sections, each section being in the form of a metal stamping having a continuous front, side and rear wall construction and a flange extending inwardly therefrom and continuous with the walls, 65 the sections being assembled with the flanges in contact, and base members above and below the flanges provided with aligned slots, whereby the container is formed with its interior divided by the flanges and base 70 members into upper and lower compartments connected only by said slots.

In witness whereof, I have hereunto signed my name.

JOSEPH KAUFMAN.
